Fig. 2.

Fig. 3.

Fig. 5.

Fig. 4.

A technical line drawing of a mechanical part, likely a handle or lever. It features a central vertical post with a slot. A horizontal bar is attached to the top of the post, with a circular hole in its center. A vertical slot is cut into the side of the post. A curved lever arm extends from the side of the post, ending in a hook. The assembly is labeled with the following numbers: 34X at the top left, 38 at the top center, 43 at the top right, 44 at the top far right, 28X at the bottom right, 40 at the bottom center, and 41 at the bottom left.

UNITED STATES PATENT OFFICE.

FREDERICK T. ARTZ, OF MANCHESTER, NEW HAMPSHIRE, ASSIGNOR, BY MESNE ASSIGNMENTS, TO DRAPER CORPORATION, OF HOPEDALE, MASSACHUSETTS, A CORPORATION OF MAINE.

AUTOMATIC FILLING-REPLENISHING LOOM.

1,265,584.

Specification of Letters Patent. Patented May 7, 1918.

Application filed October 5, 1915. Serial No. 54,271.

To all whom it may concern:

Be it known that I, FREDERICK T. ARTZ, a citizen of the United States, residing at Manchester, county of Hillsborough, State 5 of New Hampshire, have invented an Improvement in Automatic Filling-Replenishing Looms, of which the following description, in connection with the accompanying drawing, is a specification, like characters 10 on the drawing representing like parts.

This invention relates to improvements in automatic filling replenishing looms, and the principal object thereof is to provide a simplified form of feeler mechanism which may 15 be applied to the usual form of "Northrop" loom to adapt the same for use with filling carriers having feeling recesses or slots to receive the end of the feeler when the filling on the carrier is nearly exhausted.

Another object of the invention is to provide a simple but effective means of removing the feeler from feeling position upon the stoppage of the loom and for withholding the same from operative position until 25 the loom is again started under power, thereby permitting the loom to be turned over by hand and the shuttle boxed without danger of improperly initiating the action of the transferring mechanism during such manual 30 operations as may be necessary or desirable during the stoppage of the loom.

Other objects of the invention and the nature thereof will more fully appear from the following description and the accompanying drawings and will be particularly 35 pointed out in the annexed claims.

The drawings illustrate the invention as applied to the well known "Northrop" type of loom, sufficient portions of the loom being 40 illustrated to show the relative positions of the parts of the loom and the novel mechanism applied thereto.

In the drawings,

Figure 1 is a plan view, broken away in 45 the middle, of a portion of a "Northrop" loom with the present invention incorporated therein;

Fig. 2 is a view of a portion of the loom showing the improved feeler and the mechanism operated thereby to initiate the action 50 of the transfer mechanism;

Fig. 3 is a view of the controller arm and latch showing its relation to the actuating bracket carried by the weft hammer;

Fig. 4 is a detail view of a portion of the 55 same showing the latch in a different position;

Fig. 5 is an end elevation of the counter-weighted feeler mechanism.

Fig. 6 is a detail view of a means which 60 is actuated preferably by the knock-off lever to withdraw and withhold the feeler from operative position during the stoppage of the loom.

In the usual types of automatic filling 65 replenishing looms the bobbins or other filling carriers are provided with a "bunch" which is wound upon the barrel of the filling carrier a short distance from the base thereof before the main or service winding is laid. 70 The feeler is positioned to engage the filling which overlies the bunch and is operated thereby to prevent the action of the transferring mechanism. The feeler however is so set that after the service winding and a 75 predetermined portion of the "bunch" is wound off, other mechanisms are engaged which cause the operation of the transfer mechanism to remove the nearly exhausted filling carrier from the shuttle and substitute 80 a fresh carrier therefor.

In such cases the discharged filling carrier retains more or less of the bunch which must be stripped off before the filling carrier is re-wound. This entails considerable loss 85 of time as well as a substantial loss of material. In order to overcome these losses and also to avoid the necessity of such exact 90 adjustments as are required in feelers operated by "bunches" on the filling carrier, filling carriers have been devised in which the barrels are slotted or recessed to receive the end of the feeler, when the filling is sufficiently unwound to expose the slot.

The slotted or recessed filling carriers 95 may be so wound that when the feeler slot is exposed just enough filling will remain on the carrier to complete a pick from the feeler end of the loom to the battery end, leaving the filling carrier clean when discharged and thus avoiding the necessity of 100 stripping the bobbin and the wastage of filling. Furthermore such feelers may have a greater amplitude of movement when substantial exhaustion of filling is detected so 105 that the parts of the feeler may be positioned in such a manner as to avoid the likelihood of improper transfer.

The present invention is designed to provide a simple and effective feeling mechanism which may be readily substituted for the "bunch" feelers of the usual forms of automatic looms to adapt them for use with these slotted or recessed filling carriers.

The invention is illustrated herein as applied to the transfer mechanism of the "Northrop" type of loom but it will be understood that it is equally applicable to other forms of automatic looms and that it may be utilized to effect other changes in the operation of the loom.

As illustrated in the drawing the loom 15 comprises the usual breast beam 1, lay 2, with the shuttle boxes 3, 4; the hopper or battery 5, and transfer arm 6, the action of the latter being initiated through the controller rod 7 which may be actuated through the 20 mechanism positioned in the path of the weft hammer 8, or some other vibrating actuator, upon detection of failure or absence of filling either by the usual weft fork 9 or by the feeler mechanism which forms the subject 25 matter of this invention.

As illustrated herein the feeler mechanism is carried upon the shipper stand 10 which may be secured to the main frame at the end of the breast beam. The feeler bracket 30 11 desirably is secured to an extension of the shipper stand by a bolt 12 which passes through slots 13, 14 in the shipper stand and feeler bracket respectively, said slots being positioned at right angles to one another to 35 permit both vertical and lateral adjustment of the feeler.

The feeler preferably is in the form of a cylindrical rod 15 which is slidably mounted in a journal 16 in a horizontal extension 17 40 of the bracket 11 and in operation is so positioned that its end will enter the slots 18, 19 in the shuttle box 3 and shuttle 20 respectively and will register with the slot 21 in the barrel of the bobbin 22.

45 The opposite end of the feeler 15 preferably is pivotally attached to the arm 23 of a bell crank lever which conveniently may be pivoted upon a stud 24 projecting from the bracket 11, the other arm 25 of the bell 50 crank lever being connected by a link 26 to the outer end of a latch operating lever or transmitter adapted to effectively position a latch, or other member, connected with the controller rod in the path of a moving actuator such as the weft hammer. The feeler 55 15 may conveniently be retained normally in feeling position by a counterweighted arm 27 or, by a suitable spring as will readily be understood by those skilled in the art.

60 The latch operating lever or transmitter is preferably in the form of a lever 28 which preferably is pivotally mounted upon a bracket 29 which is secured to a lug 30 projecting upwardly from the shipper plate 10.

65 The bracket 29 preferably is provided with

an overhanging guide or keeper 31 slotted to receive the lever 28 and adapted to prevent lateral movement of the lever and also to limit the upward and downward movement about its pivot. In order to more accurately 70 balance the parts of the feeler mechanism and thereby increase the sensitiveness thereof, a counterweight 32 may be movably secured upon one arm of the transmitter.

The opposite end of the transmitter 28 is 75 positioned operatively to engage a latch upon an arm or member connected with the controller rod 7, and to control its position relative to the path of a moving actuator.

In the preferred embodiment of the invention illustrated herein an arm 33 is pivotally connected to a vertical extension 7* on the controller rod 7, being held in substantially horizontal position by suitable interengaging shoulders on the arm and extension. The outer end of the arm 33 preferably is bifurcated or recessed, one of the forks 34 being provided with communicating horizontal and vertical slots 35, 36 to receive the reduced end 28* of the transmitter 90 28.

A latch 38 preferably pivotally mounted between the forks 34, 34* upon a stud, normally lies just above and parallel to the horizontal slot 35, being supported upon a 95 ledge 40 on the fork 34*. When in horizontal or normal position the end of the latch 38 lies in the path of a moving actuator, which as illustrated herein is a notched plate 41 bolted upon, or forming an extension of 100 the weft hammer. The latch 38 may be provided with a tail 43 adapted to engage the shoulder 44 at the base of the bifurcated end of the arm 33 and thereby prevent the latch from being overturned.

105 In operation the filling upon the filling carrier 22 engages the end of the feeler 15 upon each beat up of the lay forcing the feeler forward (toward the breast beam) and rocking the arm 23 of the bell crank lever thereby depressing its arm 25 and through the link 26 the outer end of the transmitter 28 thus raising the inner end 28* of said lever into the slot 36 and raising the latch 38 out of the path of the extension 110 41 of the weft hammer or other actuator thus avoiding transfer. Upon substantial exhaustion of filling on the filling carrier 115 however the end of the feeler 15 will enter the slot 21 in the filling carrier so that the bell crank lever and transmitter and latch will not be actuated, the latch 38 is thereby 120 permitted to remain in the path of the actuator which will force it, and the arm 33, forward rocking the controller shaft 7 and initiating the actuation of the transferring mechanism in the manner usual in machines 125 of this type. The horizontal slot 35 in the fork 34 of the arm 33 permits this forward movement without interference with the end 130

28^x of the transmitter which not having been raised lies within said slot.

In making adjustments and repairs to the loom, and often in splicing the warp, it is 5 desirable that the feeler be withheld from feeling position during the stoppage of the loom, to prevent improper transfer or injury to the shuttle or feeler when the loom is turned over manually, and this invention 10 includes means for withdrawing and withholding the feeler from operative position so long as the shipper is out of running position.

In the preferred embodiment of the invention 15 illustrated herein the shipper 45 is shown in running position, held in the offset portion of the slot 46, the shipper being engaged by one end of the usual knock-off lever 47. The feeler withdrawing mechanism 20 may conveniently be in the form of a block 48 slidably mounted in a groove 49 in a lateral extension 50 of the bracket 29 and connected by an arm or rod 51 to the knock off lever 47 preferably by a slot and bolt connection 52 to permit sufficient relative movement 25 to compensate for the arcuate movement of the knock-off lever.

The end of the block 48 is preferably provided with a beveled portion 53 (see Fig. 6) 30 which underlies the transmitter 28 near its pivot, and provides an inclined surface or wedge adapted to raise one end of the transmitter lever when the knock off is actuated to release the shipper from running position.

During the normal operation of the loom the shipper is retained in the position illustrated in Fig. 1 and the block 48 is out of engagement with the transmitter. When 40 however the loom is stopped manually or by a usual automatic stop mechanism common to looms of this type the knock off lever is moved about its pivot thrusting the block 48 beneath the inner portion of the transmitter thus raising its end 28^x and thereby elevating the latch 38 out of the path of the vibrating actuator 41 so that transfer cannot be called for during the stoppage of the loom or while the loom is operated manually.

50 At the same time the opposite or outer end of the transmitter is depressed, forcing the link 26 and the arm 25 of the bell crank lever downward thereby rocking the other bell crank arm 23 forward and withdrawing 55 the feeler from feeling position.

The block 48 preferably is retained in its position under the transmitter during the stoppage of the loom and until the knock off lever is restored to the position in which it 60 is illustrated in Fig. 1 by the placing of the shipper in running position.

While the mechanisms herein disclosed comprise a preferred embodiment of the invention particularly adapted to the "Nor- 65 throp" type of loom it is to be understood

that the same is merely illustrative of my invention and that the same may be embodied in different forms of mechanism and may be applied to various other types of looms within the scope of the following 70 claims.

Having fully described my invention, what I claim as new and desire to secure by Letters Patent is:

1. In an automatic filling replenishing 75 loom comprising feeler mechanism and stop mechanism including a shipper and a knock-off lever therefor, means connected to the knock-off lever adapted to render the feeler mechanism inoperative during the stoppage 80 of the loom and to release said feeling mechanism upon restoration of the shipper to running position.

2. In an automatic filling replenishing 85 loom comprising feeler mechanism and stop mechanism including a shipper and a knock-off lever therefor, means connected to said knock-off lever adapted to remove the feeler 90 from feeling position upon the actuation of the knock-off lever to withhold the feeler from operative position during the stoppage of the loom and to release said feeler upon restoration of the shipper to running position.

3. In an automatic filling replenishing 95 loom having a shuttle equipped with a filling carrier having a feeler recess in the barrel thereof, transferring mechanism, a controller shaft therefor having a latch normally positioned in the path of a vibrating 100 actuator, a feeler, a bell crank lever having one arm connected to said feeler, a central pivoted transmitter connected at one end to the other arm of said bell crank lever and having its opposite end underlying said 105 latch whereby the feeler upon entering the feeling recess in the filling carrier upon substantial exhaustion of filling will permit said latch to lie in the path of the vibrating actuator and be caused thereby to initiate 110 the action of the transfer mechanism.

4. In an automatic filling replenishing 115 loom having a shuttle equipped with a filling carrier provided with a recess in the barrel thereof, transferring mechanism, a controller shaft therefor, an arm connected to said controller shaft provided at its end with communicating horizontal and vertical slots, a latch pivotally mounted upon said arm and normally overlying said horizontal 120 slot in the path of a vibrating actuator, a feeler, a bell crank lever having one arm connected to said feeler, a central pivoted transmitter connected at one end to the other arm of said bell crank lever and having its 125 opposite end extending into said horizontal slot beneath said latch and adapted normally to be actuated by said feeler upon engagement of the filling upon the filling carrier to raise said latch out of the path 130

of the moving actuator and upon the entry of said feeler into said feeling recess in the filling carrier upon substantial exhaustion of filling to permit said latch to remain in the path of the vibrating actuator whereby the action of the transfer mechanism will be insured.

5. In an automatic filling replenishing loom, transferring mechanism, feeler mechanism, a pivotally mounted transmitter connected to said feeler mechanism and operable thereby to control the action of the transferring mechanism, stop mechanism including a shipper and a knock-off lever therefor, a sliding member connected to said knock-off lever engaging said transmitter and adapted to render the transmitter inoperative upon the actuation of the knock-off lever and thereby prevent automatic action of the transferring mechanism during the stoppage of the loom and to release said transmitter upon the restoration of the shipper to running position.

6. In an automatic filling replenishing loom, transferring mechanism, controlling mechanism therefor including a latch normally positioned in the path of a vibrating actuator, a pivotally mounted transmitter having one end positioned beneath said latch and its opposite end connected to feeler mechanism whereby the presence of filling in the shuttle will actuate the feeling mechanism to cause said transmitter to raise the latch out of the path of the vibrating actuator and the substantial absence of filling will permit said latch to be engaged by said vibrating actuator, a knock-off lever, a wedge shaped slide connected to said knock-off lever and lying beneath said transmitter adapted upon actuation of said knock-off lever to raise said transmitter and thereby remove the latch from the path of the vibrating actuator.

In testimony whereof, I have signed my name to this specification.

FREDERICK T. ARTZ.
